ends are offset rearwardly. This will permit a claw hammer, or other tool, to be inserted to pry loose the impaling pins 18.

In using the tool, the body sections are opened by swinging about the hinge 3, and the rod 7 is inserted through the openings 5 in the straps 4 and the openings 6 in the body section 1. Rod 7 is pushed through the openings far enough to project substantially the same distance on each side of the body. The handle 8 is swung downwardly from the recess 10 about its hinge 9, and, with wing nut 17 adjusted so that head 12 may be moved about the pivot bolt 16 but will not swing freely thereon, the tool is lifted until the head is substantially flush with the ceiling line. The tool is then thrust forward to sink the impaling pins 18 into the side wall of the room. In most cases, the pins will penetrate the horizontal stringers which form part of the room framing and lie adjacent the ceiling. The tool will then be firmly anchored at its free end and will support the ceiling board. The adjustability of the head permits attachment to supports at various angles, and makes it possible to anchor to members which otherwise would be inaccessible. The board is placed upon the body of the tool while the tool is in an inclined position, the end of the board being pressed firmly against the side wall framing. The outer end of the tool is then lifted to position the board against the ceiling joists. The handle permits the workman to achieve this while standing on the floor. The board may then be held while being secured in place. During the lifting and holding operation, the body of the tool supports the board longitudinally, while rod 7 and head 12 furnish transverse support. When the tool is not in use it may be folded about the hinges 3 and 9 into compact form for storing or transporting to another job.

While in the above, one practical embodiment of the invention has been disclosed in detail, it will be understood that many changes may be made from the precise structure shown and described within the scope of the invention as defined by the appended claims.

What is claimed is:

1. In a lifting tool, a pair of hingedly connected body sections, each having a longitudinal axis, a handle hingedly connected to the free end of one of said body sections, a supporting head pivotally connected to the free end of the other body section, and means to lock said body sections in longitudinal alignment, a part of said locking means comprising a rod projecting beyond opposite sides of said body sections to form a transverse support for material to be lifted upon the tool.

2. In a lifting tool as claimed in claim 1, said head extending transversely to the direction of said body and having impaling pins projecting therefrom, whereby said head will cooperate with said rod in transversely supporting material to be lifted upon said tool.

3. In a lifting tool as claimed in claim 1, a recess in the body section carrying said handle to receive said handle when folded.

4. In a lifting tool as claimed in claim 1, said head being positioned transversely to the direction of said body and having impaling pins projecting from spaced points thereon, and means for binding said head to said body to prevent free pivotal movement of said head with respect to said body.

5. In a lifting tool as claimed in claim 1, said head being positioned transversely to the direction of said body and having impaling pins projecting from spaced points thereon, said pins having their butt ends joined to the head on a common plane and a portion of said head being raised out of the plane of joinder of the butt ends of the pins with said head to provide an engaging surface for removing the pins from a support.

body sections, a supporting head pivotally connected to the free end of one of said body sections, a handle hingedly connected to the free end of the other said body section, and means to lock said body sections in longitudinal alignment, a part of said locking means comprising a rod projecting beyond opposite sides of said body sections to form a transverse support for material to be lifted upon the tool.

2. In a lifting tool as claimed in claim 1, said head extending transversely to the direction of said body and having impaling pins projecting therefrom, whereby said head will cooperate with said rod in transversely supporting material to be lifted upon said tool.

3. In a lifting tool as claimed in claim 1, a recess in the body section carrying said handle to receive said handle when folded.

4. In a lifting tool as claimed in claim 1, said head being positioned transversely to the direction of said body and having impaling pins projecting from spaced points thereon, and means for binding said head to said body to prevent free pivotal movement of said head with respect to said body.

5. In a lifting tool as claimed in claim 1, said head being positioned transversely to the direction of said body and having impaling pins projecting from spaced points thereon, said pins having their butt ends joined to the head on a common plane and a portion of said head being raised out of the plane of joinder of the butt ends of the pins with said head to provide an engaging surface for removing the pins from a support.
